DESIGN FOR A REFRIGERATED VEGETABLE DISPLAY CASE

George J. Hopkins, Kendallville, Ind., assignor
to McCray Refrigerator Company, Kendall-
ville, Ind., a corporation of Indiana

Application September 27, 1937, Serial No. 71,804

Term of patent 7 years

To all whom it may concern:

Be it known that I, George J. Hopkins, a citizen of the United States, residing at Kendallville, in the county of Noble and State of Indiana, have invented a new, original, and ornamental Design for a Refrigerated Vegetable Display Case, of which the following is a specification, reference being had to the accompanying drawing, forming a part thereof, in which:—

The figure is a front perspective view of a refrigerated vegetable display case showing my new

design, the distinguishing, essential and dominant features or characteristics of the design being the superstructure with its inclined mirror, the glass enclosed storage space for the display of vegetables, and the recessed bottom portion as shown. The rear surface of the cabinet is plain and of conventional type.

I claim:

The ornamental design for a refrigerated vegetable display case as shown and described.

GEORGE J. HOPKINS.
